(57) **CLAIM**

The ornamental design for a cable management ring, as shown and described.

DESCRIPTION

FIG. 1 is a top perspective view of a cable management ring showing my new design;

FIG. 2 is a bottom perspective view thereof;

FIG. 3 is a right elevational view thereof;

FIG. 4 is a left elevational view thereof;

FIG. 5 is a top view thereof;

FIG. 6 is a bottom view thereof;

FIG. 7 is a front elevational view thereof;

FIG. 8 is a back elevational view thereof; and,

FIG. 9 is a perspective view of the cable management ring of FIG. 1 shown surrounding a bundle of wires which are shown in broken lines for illustrative purposes only and form no part of the claimed design.
